UNITED STATES PATENT OFFICE.

PHILIP W. MOORE, OF EVANSTON, ILLINOIS, ASSIGNOR TO THE P. & M. COMPANY, OF CHICAGO, ILLINOIS, A CORPORATION OF ILLINOIS.

RAIL-ANCHOR.

1,128,349.

Specification of Letters Patent. Patented Feb. 16, 1915.

Original application filed December 15, 1913, Serial No. 806,773. Divided and this application filed October 5, 1914. Serial No. 865,087.

To all whom it may concern:

Be it known that I, PHILIP W. MOORE, a citizen of the United States, residing at Evanston, in the county of Cook and State of Illinois, have invented certain new and useful Improvements in Rail-Anchors, of which the following is a specification.

My invention relates to the class of devices known as rail anchors, rail stays, or anti-creepers, the purpose of which is to provide an engagement between railroad rails and the ties on which they are laid (or other stationary, or relatively stationary, elements of the road-bed) which checks the well known tendency of rails, under certain conditions, to creep in the direction of their length; and the object of the invention is to provide a simple, inexpensive device of this type which will be strong, light in weight and so constructed that the tendency of the rail to which it is applied to move longitudinally is self checking.

The invention contemplates particularly the type of rail anchor utilizing wedge action between relatively movable parts of the device for effecting the grip of the device on the rail; and the object of the invention, more particularly, is to provide a construction and design of the co-engaging parts of the anchor whereby any tendency on the part of the rail to move forward produces a very powerful and intimate wedging action between said parts resulting in the checking of the creeping tendency.

With this object in view the anchor consists of two elements, one of which bears against the tie and the other stands away from the same; one element consisting of a yoke or shoe which extends under the base of the rail and engages the same at opposite edges, said yoke being made preferably, though not necessarily, of a single integral structure which may be either rigid or slightly flexible as desired, the other consisting of a wedge element interposed between the yoke and the rail which wedge element is subjected to lateral stresses tending to deform or strain the same in directions transversely of the rail when the forward thrust of the rail moves, or tends to move the free element of the anchor toward the tie against which the other element is abutted.

The invention has for further objects such other new and improved constructions, ar-

rangements and devices relating to rail anchors as will be hereinafter described and claimed.

This application is a division of my co-pending application Serial No. 806,773, filed December 15, 1913.

The invention is illustrated, in a preferred embodiment, in the accompanying drawings wherein—

Figure 1 shows a rail anchor, constructed in accordance with the invention, applied to a rail, the rail being shown in section and the tie against which the device is abutted in elevation. Fig. 2 is a plan view of the rail anchor, rail and tie shown in Fig. 1; Fig. 3, a sectional elevation taken on line 3—3 of Fig. 2; Fig. 4, a vertical sectional view, with the rail shown in elevation, taken on line 4—4 of Fig. 1; Fig. 5, a view, in perspective, of the wedge element, and Fig. 6, a similar view of the yoke element.

Like characters of reference designate like parts in the several figures of the drawings.

Referring to the drawings, A designates a railroad rail to which the device is applied, and B one of the cross ties on which the rail is laid. The anchor consists of a yoke member C (Fig. 6) and a hollow wedge member D. The yoke member C is made up of a bar of metal, the ends of which are bent over so as to form hooks 10 which bear against the opposite edges of the rail base 11. The bar is thicker at the edge 12 remote from the tie than at the opposite edge 13 and is bent at the middle as shown at 14, or is otherwise formed so that when the yoke is in position on the rail two wedge faces 15, 15 are provided which have a downward slope in the direction toward the tie and inwardly toward the center axial line of the rail base.

The wedge member D consists of a tie abutting member 16, a pair of wedge members 17, and a connecting web 18, the members 17 diverging from the connecting web toward the tie abutting member. The wedge members 17 are formed with preferably rounded wedge surfaces 19 which have an inclination corresponding generally to the inclination of the surfaces 15 on the yoke.

The anchor is applied to the rail by placing the wedge element under the base flange of the rail with its tie abutting member 16

bearing against the tie, placing the yoke on the base flange of the rail back of the wedge element, and driving it toward the tie as far as it will go. When the parts of the anchor 5 have been brought in this manner into intimate contact with each other and with the rail, the forward thrust imparted by the wheels of the train to the rail will be transmitted to the free element or yoke C of the 10 anchor, and thence to the wedge members 17 of the hollow structure D. The stresses exerted against the hollow member D would, if not resisted, tend to force the wedge members 17 inwardly toward each other. As the 15 hollow structure D is made capable of withstanding these stresses without being broken or suffering any considerable strain, a wedging action is produced between the parts of the anchor and between the anchor and the 20 rail base which checks the forward thrust of the rail. The hollow configuration of the wedge member necessarily gives it a certain elasticity laterally whereby the hold between the elements is made more intimate 25 and vibration is absorbed, minimizing the tendency of the parts to work loose.

While I have shown and described my invention as embodied in a preferred construction, modifications in the form and proportion 30 of the parts might be made without departure from the principles of the invention.

I claim:

1. In a rail anchor, the combination with 35 a bar formed at opposite ends with hooks adapted to bear against the upper surfaces of the base flange of the rail, of a tie abutting plate, and separate wedge members formed on said plate with an open space intervening between them, which extend under 40 opposite edges of the base flange of the rail and intervene between said bar and the bottom of the rail directly under said hooks.

2. In a rail anchor, the combination with 45 a bar formed at opposite ends with hooks adapted to bear against the upper surfaces of the base flange of the rail, of a tie abutting plate, and wedge members formed on said plate adapted to intervene between said bar and the bottom of the rail directly under 50 said hooks, said bar and wedge members being formed with coacting surfaces having an inclination with respect to the plane of the rail base both longitudinally and transversely thereof.

3. A rail anchor comprising two relatively 55 movable elements, one adapted to extend around the base flange of the rail and provided with overlapping parts adapted to bear against the upper surfaces of the base 60 flange on opposite sides of the rail, the other providing wedges which extend under opposite edges of the base flange of the rail directly under the overlapping parts of the first named element, said wedges and the 65 element with which they are engaged being

formed with coengaging surfaces which are oblique to the plane of the bottom of the base flange both longitudinally and transversely of the rail.

4. A rail anchor comprising two relatively 70 movable elements one adapted to extend around the base flange of the rail and provided with overlapping parts bearing against the upper surfaces of the base flange of the rail on opposite sides thereof, the 75 other providing a tie abutting plate and a pair of wedges which extend under opposite edges of the bottom of the rail directly under the overlapping parts of the first named element, said wedges and the element with 80 which they are engaged being formed with coengaging surfaces which are oblique to the plane of the bottom of the base flange both longitudinally and transversely of the rail. 85

5. A rail anchor comprising a bar formed at opposite ends with hooks adapted to bear against the upper surfaces of the base flange of the rail on opposite sides thereof, and a tie abutting plate formed with a pair of 90 wedge members which diverge in the direction of said plate and are connected at their outer ends by a cross piece, said wedge members being adapted to intervene between the bottom of the base flange and said bar and 95 said member and bar being formed with coacting wedge faces which have an inclination with respect to the plane of the base of the rail both transversely and longitudinally thereof. 100

6. In a rail anchor, the combination with a bar formed with hooks at opposite ends adapted to bear upon the upper surfaces of the base flange of the rail on opposite sides thereof, of a wedging structure which is hollow so as to be slightly elastic adapted to intervene between the bottom surface of the rail base and said bar, said bar and hollow structure being formed with two pairs of coacting wedging faces and one of said elements being provided with a tie abutting member. 105

7. In a rail anchor, the combination with a yoke element adapted to extend under the base of a rail and to engage said rail base on 110 opposite sides thereof, of a wedge element intervening between the rail and said yoke, one of said elements being adapted to bear against a tie and the other to stand away from the same; said wedge element formed 115 with two wedge members having an open space intervening between them, and the yoke with wedge surfaces engaged by said wedge members so disposed that the movement of the free element toward the tie exerts transverse stresses against said wedge members. 120

8. In a rail anchor, the combination with a yoke element adapted to extend under the base of a rail and to engage said rail base on opposite sides thereof, of a wedge element 125

interposed between the rail and said yoke, said wedge element being formed with a tie abutting member, with two wedge members projecting therefrom and with a connecting web at the opposite extremities of the wedge members, and the yoke element being adapted to stand away from the tie and formed with wedge surfaces engaged by said wedge members so disposed that the movement of the yoke element toward the tie produces transverse stresses against said wedge members inwardly in opposite directions. 5

9. In a rail anchor, the combination with a yoke member adapted to extend under the base of a rail and to engage said rail base on opposite sides thereof, of a wedge element intervening between the rail and said yoke, one of said elements being adapted to bear against the tie and the other to stand away from the same, said wedge element consisting of a hollow slightly compressible structure formed with wedging faces and the yoke with correspondingly inclined 20 wedge surfaces. 25

10. In a rail anchor, the combination with a yoke member adapted to extend under the base of a rail and to engage said rail base on opposite sides thereof, of a wedge element intervening between the rail and said yoke, one of said elements being adapted to bear against the tie and the other to stand away from the same, said wedge element formed with two wedge members having an open space intervening between them and the yoke with wedge surfaces engaged by said wedge members so disposed that the movement of the free element toward the tie produces transverse stresses against said 35 wedge members. 40

11. In a rail anchor, the combination with a yoke member adapted to extend under the base of a rail and engage said rail base on opposite sides thereof, of a wedge element intervening between the rail and said yoke, one of said elements being adapted to engage the tie and the other to stand away from the same; said wedge element being formed with wedge members having an 45 open space intervening between them, which members diverge in the direction of said tie and the yoke element with surfaces engaged by said wedge members having a downward slope in the direction toward the 50 tie and toward the center of the rail base. 55

12. In a rail anchor the combination with a yoke member adapted to extend under the base of a rail and engage said rail base on opposite sides thereof, of a wedge element 60 intervening between the rail and said yoke,

said wedge element formed with a tie abutting member, with wedge members having an open space intervening between them, which members project convergently therefrom and a connecting web, and the yoke 65 member being adapted to stand away from the tie and formed with surfaces engaged by said wedge members having a downward slope in the direction toward the tie and toward the center of the rail base. 70

13. In a rail anchor, the combination with a yoke adapted to extend under the base of a rail and engage said rail base on opposite sides thereof, of a wedge element hollow so as to be slightly elastic interposed between 75 the yoke and said rail base. 75

14. In a rail anchor, the combination with a yoke adapted to extend under the base of a rail and engage said rail base on opposite sides thereof, of a wedge element hollow so 80 as to be slightly elastic interposed between the yoke and said rail base, said yoke and wedge element being formed with co-engaging surfaces whereby the movement of one element relative to the other in the direction 85 toward the tie produces transverse stresses against the hollow wedge member. 85

15. In a rail anchor, the combination with a yoke adapted to extend under the base of a rail and engage said rail base on opposite 90 sides thereof, of a wedge element hollow so as to be slightly elastic interposed between the yoke and the rail base and formed with a tie abutting member. 90

16. A rail anchor comprising two elements 95 having a wedging engagement one with the other, one of said elements consisting of a pair of integrally united wedges having an open space intervening between them which are subjected to transverse stresses by virtue 100 of the wedging action between said elements. 100

17. A rail anchor comprising two elements having a wedging engagement one with the other, one of said elements consisting of a hollow slightly elastic structure 105 which is subjected to transverse stresses by virtue of the wedging action between said elements. 105

18. A rail anchor comprising two elements 110 having a wedging engagement one with the other, one of said elements consisting of a hollow slightly compressible structure which is subjected to transverse crushing stresses toward each other by virtue of the wedging 115 action between said elements. 115
